F. A. THURMAN

BOX

Filed Aug. 11, 1924

UNITED STATES PATENT OFFICE.

FRED A. THURMAN, OF APACHE, OKLAHOMA.

BOX.

Application filed August 11, 1924. Serial No. 731,412.

The present invention relates to a box designed particularly for carrying tackle, ammunition, lunch or the like.

An important object of the invention is to provide a box of this nature having means whereby it may be easily attached to the belt of a person in order that it may be conveniently carried about and in order that access may be readily had thereto.

Another important object of the invention is to provide a box of this nature having removable partitions and a removable tray the various parts of which may be assembled or disassembled very easily.

A still further important object of the invention is to provide a box of this nature possessing a very simple and efficient construction, one which is reliable, inexpensive to manufacture, strong, durable, and well adapted to the purpose for which it is designed.

With the above and numerous other objects in view as will appear as the description progresses, the invention resides in certain novel features of construction, and in the combination and arrangement of parts as will be hereinafter more fully described and claimed.

In the drawing,

Figure 1 is a perspective view of the box embodying the features of my invention showing a belt fragmentarily with the box mounted thereon,

Figure 2 is a top plan view of the box showing the same open,

Figure 3 is a detail perspective of the removable frame,

Figure 4 is a top plan view of the box of the frame and cover removed, and

Figure 5 is a perspective view of one of the removable partitions.

Referring to the drawing in detail it will be seen that the box indicated generally by the letter D consists of a bottom 5, side walls 6, outer wall 7 and inner wall 8. The inner and outer walls are turned concentric with each other the former being shorter than the latter. A hinge 9 is provided on the upper edge of the outer wall 7 and a cover 10 is mounted thereon so as to be capable of closing over the box and to be held in such position by means of a clip 11 attached to the inner wall 8. A suitable handle 12 is provided on the cover 10 in order that the box may be carried about thereby. On the inner wall there are disposed two

sleeves 13 for receiving one arm of the S-shaped hangers 14 the hook portions 15 of which are adapted to engage a belt as is illustrated to advantage in Figure 1. The 60 arms of these hangers 14 which pass through the sleeves have their terminals bent to one side as is indicated at 16 so that the hangers are held against displacement in the sleeve brackets 13. 65

A pair of channel irons 17 are disposed within the box, one fixed to the inner face of each side wall 6 and a curved partition 18 having its ends engaged therewith in order that it may be easily removed when de- 70 sired.

A third channel iron is mounted on the inner face of one of the side walls 6 and a fourth channel iron 21 is mounted on the convexed side of the curved partition 18 for receiving the partition element 22 which consists of the straight transverse wall 23 and the curved longitudinal wall 24 extending from an intermediate portion of the wall 23. The free end of the wall 24 is adapted to be 80

received in channel iron 20 while the channel iron 21 receives one end of the wall 23 and the other end is disposed against the inner surface of the outer wall 7. The angle iron 20 is equal in height to the height of 85 wall 24 whereas angle iron 21 is equal in height to wall 18 and the side of its upper portion is broken away in order that a tray indicated generally by the letter T may be received as is illustrated to advantage in Figure 2. This tray consists of a 90

bottom 26, the outer curved wall 27, the inner curved wall 28, and the end walls 29. A transversely extending partition 30 is provided in the tray and two longitudinally extending curved partitions 31 are disposed between it and the side walls 29. This tray is adapted to rest on the walls 23 and 24 of the partition element 22 being held in place by the upper portion of the channel iron 21. 100

From the above description it will be seen that the box is capable of being very easily attached to the belt of a person and that the cover may be opened to swing outwardly from the person in order that ready access may be had to the interior of the box. It is also to be noted that the partitions and the tray may be easily assembled or disassembled in respect to the box. Although I have described the invention with a certain degree of particularity, it is desired to point out 110 that numerous changes in the details of con-

struction, and in the combination and arrangement of parts may be resorted to without departing from the spirit or scope of the invention as hereinafter claimed or sacrificing any of its advantages.

Having thus described my invention, what I claim as new is:

1. A box of the class described including a pair of channel irons disposed interiorly thereof, a partition engaged with said channel irons in order that it may be removed, a third channel iron on the partition, a fourth channel iron on the interior of the box, and a substantially T-shaped partition

having two of its terminals engaged with the third and fourth channel irons all in the manner and for the purpose specified.

2. In a box of the class described, a pair of channel irons disposed therein, a T-shaped partition element having two of its terminals engaged with said channel irons, said channel irons extending upwardly beyond the partition and a tray disposed within the box resting on the partition and held in place by the upstanding channel irons.

In testimony whereof I affix my signature.

FRED A. THURMAN.
